US0D1092204S

(12) United States Design Patent (10) Patent No.: US D1,092,204 S
(45) Date of Patent: * Sep. 9, 2025

(54) FOOD CARTON

(71) Applicant: Inno-Pak, LLC, Delaware, OH (US)

(72) Inventors: Jonathan D. Sill, Delaware, OH (US);
Steven A. Mayer, Indianapolis, IN (US)

(73) Assignee: Inno-Pak, LLC, Delaware, OH (US)

() Term: 15 Years

(21) Appl. No.: 29/895,184

(22) Filed: Jun. 19, 2023

Primary Examiner — Catherine S Posthauer

Assistant Examiner — Joan E. Diehl

(74) Attorney, Agent, or Firm — Ward and Smith, P.A.;
Ryan K. Simmons

(57) CLAIM

The ornamental design for a food carton, as shown and described.

DESCRIPTION

FIG. 1 is a perspective view of a food carton showing a new design;

FIG. 2 is a perspective view of the food carton of FIG. 1 showing an alternate embodiment; and,

FIG. 3 is a perspective view of the food carton of FIG. 1 showing an alternate embodiment.

In the drawings the dotted lines are for the purpose of illustrating perforations and form part of the claimed design; the dot-dash lines depict the claim boundary and form no part of the claim; and the dash-dash broken lines are for the purpose of illustrating parts of the food carton that form no part of the claimed design.

1 Claim, 3 Drawing Sheets
